UNITED STATES PATENT OFFICE.

SYLVESTER T. COHANE, OF HARTFORD, CONNECTICUT.

FORCEPS.

1,376,005.

Specification of Letters Patent. Patented Apr. 26, 1921.

Application filed March 4, 1920. Serial No. 363,144.

To all whom it may concern:

Be it known that I, SYLVESTER T. COHANE, a citizen of the United States, residing at Hartford, in the county of Hartford and 5 State of Connecticut, have invented certain new and useful Improvements in Forceps, of which the following is a specification.

This invention relates to forceps such as used by dentists. The instrument of my invention is duplex in character being convertible so that it can be readily and quickly changed from a condition adapting it to extract one or more teeth from the upper jaw to one or more teeth from the lower jaw 10 or vice versa. The article is susceptible of inexpensive construction and when its parts are assembled, it possesses all the strength of the present implement and can be readily used. As a matter of fact it can be employed exactly as is the instrument at present in everyday use yet obviously as I have observed it has a far greater range of possibilities.

In the drawings accompanying and forming part of the present specification I have shown in detail one of the several forms of embodiment of the invention which to enable those skilled in the art to practise the same will be set forth fully in the following 25 description. I am not restricted to this disclosure as I may depart therefrom in several respects within the scope of the invention defined by the claims following said description.

35 Referring to said drawings:

Figure 1 is a top plan view of forceps involving the invention.

Fig. 2 is a side elevation of the same.

Fig. 3 is a top plan view of an end portion 40 for instance the left end portion in Figs. 1 and 2.

Fig. 4 is a cross section of one of the elements and

Fig. 5 is a top plan view of the same.

45 Like characters refer to like parts throughout the several views which are on different scales.

The instrument involves in its make up two members the levers 2 and 3 answering 50 satisfactorily in this connection. The levers 3 may as shown, be outwardly bowed or curved between their ends and milled or roughened on their outer surfaces as more or less common in the usual type of forceps. 55 The head end portion of each lever is mortised as at 4 near the opposite ends thereof

the under side of each mortise being flattened as at 5. It will be understood that the mortised portions 4 are alternately flexibly connected and at this time a flat surface 60 5 will engage against a like flat surface of the respective levers opposite ends of which are shown as in assembled relation in Figs. 1, 2 and 3. Each of the levers is provided as shown with a pivot or stud 6 rising from 65 one of the flat surfaces 5 thereof the bodies of the respective pivots or studs being practically cylindrical while their heads 7 as illustrated are elliptical or virtually so, their longitudinal axes being transverse to the 70 axis of the lever which carries them. As will be understood each of the two levers as 2 and 3 carries a pivot or stud 6 near one of its ends and about midway of one of the flat bearings and engaging surfaces 5, the 75 other surfaces having slots or openings 8 practically of elliptical form which receive the respective studs the slots or openings 8 extending through the mortises or rabbets 4 to which I have referred.

80 In Fig. 1 the two levers 2 and 3 are shown as assembled. When in this relation two flat surfaces 5 will be superimposed. To disconnect the levers they are brought practically to right angular relation with each 85 other as indicated by dotted lines. When this is accomplished the elliptical hole or slot 8 is brought into exact register with the connecting head 7 to permit the lifting apart of the two levers, at which time if 90 the reversed condition is desired the two levers are brought into right angular relation to which I have alluded, and the other headed stud or pivot 6 projected through the second coöperating slot or opening 8, the 95 levers being then brought into the engaging relation in the manner set forth to bring a flat face of a lever against a flat face of the other lever when they are brought into working relation as shown for instance in 100 Fig. 3.

The levers 2 and 3 terminate at their ends in angular jaw portions 9 which are shaped in the customary fashion but which extend oppositely to adapt one pair such as that 105 shown on the right in Fig. 2 to the upper set of teeth while the one on the left is intended to coöperate with the lower set of teeth.

I have termed the invention forceps for the reason that the article has been found 110 of particular utility in this especial field. It is possible that the construction may be

used in other connections. For instance the jaw members may be of such a shape to adapt the instrument to act as duplex pliers or for other analogous uses.

5 What I claim is:

1. An implement of the class described, comprising levers each having a jaw member at its ends and means for interchangeably pivotally connecting the levers to put

10 coöperating jaw members alternately into operative relation with each other.

2. Dental forceps comprising levers each equipped with a jaw member at its ends,

the jaw members being formed to coöperate in pairs, one adapted to an upper set of 15 teeth, and the other to a lower set of teeth, the levers having headed studs near their ends, the heads of the studs being of elliptical formation, and the levers having elliptical slots to alternately receive the studs. 20

In testimony whereof I affix my signature in the presence of two witnesses.

SYLVESTER T. COHANE
